UNITED STATES PATENT OFFICE.

HENRY L. ROGERS, OF TORONTO, ONTARIO, CANADA.

INTERNAL-COMBUSTION ENGINE.

1,197,546.

Specification of Letters Patent.

Patented Sept. 5, 1916.

Application filed August 28, 1913. Serial No. 787,135.

To all whom it may concern:

Be it known that I, HENRY LAUNDER ROGERS, a subject of the King of Great Britain, and resident of the city of Toronto, 5 county of York, Province of Ontario, in the Dominion of Canada, have invented certain new and useful Improvements in Internal-Combustion Engines, as described in the following specification, and illustrated 10 in the accompanying drawings, that form part of the same.

The principal feature of the invention consists in the arrangement of an auxiliary inlet to the cylinder, whereby a supply of air 15 or air and water in a finely divided state is introduced into the cylinder separate from the charge of combustible gas being so directed as to remain separate as far as possible from the combustible gas until ignition 20 takes place utilizing the heat units which are usually absorbed and wasted in the cylinder walls converting the thermal energy into kinetic energy and effecting the cooling of the cylinder.

25 The principal objects of the invention are, to utilize the thermal energy of the gases of combustion to the fullest extent in the operation of the engine, and to effect a saving of fuel.

30 A further and very important object is to provide within the cylinder a stratum of a heat absorbing element which will centralize the intense heat of combustion protecting the cylinder walls from excess expansion so that in large engines of high 35 power it will be possible to increase the diameter of the cylinder and will also eliminate many of the difficulties incident to water cooling the cylinder.

40 It is a well known fact that the thermal energy of the explosion within the cylinder is wasted to a great extent in the present types of internal combustion engines and I propose to introduce into the cylinder a 45 charge of water in vaporous form bringing it into contact with the walls of the explosion chamber to effect the cooling of the cylinder and to convert the vapor into an expansive gas which will upon ignition of 50 the more explosive gas be expanded to assist in the propulsion of the piston.

In the drawings, Figure 1 is a longitudinal sectional view of a portion of the preferred form of cylinder for carrying this 55 invention into effect. Fig. 2 is a longitudinal sectional view of a portion of a

cylinder showing a modified application of the invention. Fig. 3 is a reduced transverse sectional view through the line *a—b* Fig. 2.

Like numerals of reference indicate corresponding parts in each figure.

In the form of the device shown in Fig. 1, 1 is the main portion of the cylinder in which the piston 2 operates. The head end 65 3 of the cylinder is here shown slightly reduced and formed with the side walls 4 leading from a laterally arranged valve chamber 5 and flaring outwardly toward the walls of the main portion of the cylinder. 70 6 is the fuel gas inlet connection, here shown secured in the top of the head 3 and extending inwardly therefrom and formed with an annular wall 7 flaring outwardly in an inverted cup-shape, the inner edge 8 being 75 curved slightly inward toward the center. This cup shaped wall forms a chamber 9 within the cylinder head in which the explosive gas is compressed and fired. The member 6 is connected to the ordinary carbureter (which is not shown) and is provided with a valve seat 10 at the top of the combustion chamber 9 and an inlet valve 11. 80 12 are a plurality of spirally arranged ribs formed on the outer side of the cup shaped 85 wall 7. 13 is the igniter plug secured in the connection 6 and extending into the combustion chamber 9 adjacent to the inlet port 12. 14 is the exhaust port closed by a valve 15. 16 is the auxiliary inlet port here shown 90 arranged in the wall of the valve chamber 5 above the exhaust port 14 and closed by a suitable valve 17, said port having communication with a suitable form of vaporizer. I have not shown any means for operating these valves as they can be operated 95 in many ways and timed to open and close the respective ports at the desired periods.

In the operation of this form of engine the inlet valve opens the port 10 at the proper period in relation to the suction stroke of the piston and a charge of explosive gas is drawn into the central chamber 9 and follows the piston downwardly into the cylinder. The piston is preferably 100 formed with an annular flange 18 on its head of about the same diameter as the inwardly curved portion of the wall of the chamber 9 and co-acts with said wall to centralize the combustible gas. The valve 105 17 is operated to open the auxiliary inlet port 16 coincident with the opening of the

port 10 and a charge of air or air and water vapor is drawn into the valve chamber 5 and is directed into the cylinder through the annular passage 19 between the flaring wall 4 and the wall 7, being thus directed against the inner wall of the main portion of the cylinder 1. The air or vapor in flowing through the passage 19 contacts with the spiral ribs 12 which impart a swirling motion. The combined outward direction and swirling movement cause the air or vapor to follow down the side walls of the cylinder, keeping it more or less separate from the explosive gas drawn into the central portion through the inlet 10. The effect of this cool charge being directed against the cylinder wall is that the heat absorbed by the cylinder wall during the explosion and exhaust strokes of the piston is absorbed inwardly instead of being radiated outwardly. The outer stratum of water vapor and air and the spiral motion imparted to it by the vanes keeps it from readily mingling with the explosive gas and it therefore preserves to a large degree the centralization of the explosive gas even during compression and there will be no dilution or weakening of the explosive gas within the cup shaped combustion chamber where the spark plug is located. On the completion of the compression stroke the ignition of the explosive gas in the chamber 9 takes place and as the piston recedes from the cylinder head in the power stroke the exploded gas spreads outwardly and mingles with the outer stratum of vapor expanding it, thus using the thermal energy of the explosion to the greatest advantage and incidentally minimizing the absorption of heat by the cylinder walls. During the exhaust stroke the exhaust gases escape through the port 14 circulating around the wall of the combustion chamber 9 imparting the heat contained therein to the said wall and to the outer wall of the cylinder head which heat is utilized in heating and expanding the fresh charge of air and vapor brought in through the inlet 16. The opening of the exhaust releases the burnt gases and on the opening of the inlet 12 the fresh charge drawn in during the suction stroke will clear out what burnt products are left from the combustion chamber 9. There will therefore always be a charge of fresh and highly combustible gas in the chamber 9 to receive the ignition and though the remaining portion of the compressed gas within the cylinder may be rarefied to such an extent that it would not ignite with the spark such rarefied gas will ignite and explode upon the initial explosion of the richer gas. It will thus be seen that in the operation of the engine the amount of fuel gas used may be greatly reduced. The supply to each of these inlets will of course be controlled sep-

arately in the usual manner of throttling and the throttles may be operated according to the requirements of the engine in operation.

The form of device shown in Fig. 1 appears to be the most desirable but it must be understood that the principle involved may be carried out in various ways without departing from the spirit of the invention and while I have not shown the cylinder water jacketed it may be found expedient to do so as the heat of combustion may not be dissipated to such an extent that the cylinder walls would not be heated to too high a temperature.

In Fig. 2 I show the application of my invention to the ordinary T type of cylinder head having the exhaust 20 at one side and the gas intake 21 on the other side. The auxiliary inlet 22 is arranged in the exhaust side of the head. In utilizing this style of engine the top 23 of the cylinder head is formed with a transversely arranged baffle flange 24 and a plurality of transversely radiating ribs 25 extending toward the exhaust. In this form the explosive gas is directed inwardly and downwardly at one side of the cylinder and the vaporized air entering through the auxiliary inlet 22 is brought into contact with the radiating ribs 25 and directed downwardly around the inner walls of the cylinder. The combustion chamber 26 in which the spark plug 27 is located will retain a supply of the explosive gas so that the primary ignition will take place in a similar manner to that described.

In constructing an engine with an auxiliary inlet to be utilized in the manner described the energy of the heat of combustion is more fully utilized and incidental to this feature in small engines the cylinders not requiring water jackets are therefore of much lighter and neater construction and the elimination of water cooling obviates the many difficulties incidental thereto such as defective radiators and the difficulties of extremes of temperature and the proper regulation of the temperature of the cylinders.

By the present method the walls of the cylinder are kept at a much more constant and lower temperature by the direction of the cool vaporized air thereagainst and the fracturing of the metal through excessive expansion will be obviated.

What I claim as my invention is:

1. In an internal combustion engine, a cylinder formed with the side walls converging inwardly at the head end and having an inlet through the convergent portion communicating with an auxiliary air or water vapor supply, a main inlet centrally arranged in the head and connected with a fuel supply, an annular baffle surrounding said main inlet and projecting into the

- cylinder and separating the fuel inlet from the auxiliary air inlet said baffle flaring toward the cylinder walls and with the convergent portion thereof forming an annular 5 passage adapted to direct the indrawn air or vapor from the auxiliary inlet in an outward direction toward the main cylinder walls to form a stratum of a cooling medium between the cylinder walls and the 10 combustible charge.
2. In an internal combustion engine, a cylinder formed with a convergent annular passage in the head open to communication with the cylinder at the bottom and having 15 a lateral valve chamber communicating therewith, an inlet passage leading to said valve chamber from an air or water vapor supply, an exhaust passage leading from said valve chamber, a valve closing said exhaust passage, a main fuel inlet arranged in the cylinder head and entering the cylinder independent of the annular inlet passage, the walls of said inlet passage extending inwardly into the cylinder and forming a 20 central combustion chamber, a valve con- 25
- trolling the inlet, and an ignition member arranged in said combustion chamber.
3. In an internal combustion engine, a cylinder having an annular wall extending inwardly from the head and spaced from the cylinder wall and forming a central combustion chamber, a fuel inlet leading to the combustion chamber, an exhaust communicating with the passage between the cylinder wall and the wall of said combustion chamber, an auxiliary inlet leading to the passage surrounding said combustion chamber and adapted to communicate with a supply of air or vapor, and a plurality of spirally arranged ribs projecting into the 30 passages surrounding the combustion chamber. 35

Signed at the city of Toronto, county of York, Province of Ontario, in the Dominion of Canada, this 22d day of August, 1913.

HENRY L. ROGERS.
